US0D1048627S

(12) **United States Design Patent** (10) **Patent No.:** **US D1,048,627 S**
(45) **Date of Patent:** **** Oct. 22, 2024**

(54) **CLEANING ARTICLE**

(71) Applicant: **Dongguan Jiajieshi Technology Co., Ltd.**, Dongguan (CN)

(72) Inventor: **Bifeng Yuan**, Heyuan (CN)

(73) Assignee: **Dongguan Jiajieshi Technology Co., Ltd.**, Dongguan (CN)

(**) Term: **15 Years**

(21) Appl. No.: **29/950,463**

(22) Filed: **Jul. 2, 2024**

(30) **Foreign Application Priority Data**

Jun. 18, 2024 (CN) 202430372432.X

(51) **LOC (14) Cl.** **07-05**

(52) **U.S. Cl.**

USPC **D32/40**

(58) **Field of Classification Search**

USPC D32/15, 32, 35, 51, 40, 49, 50
CPC A47L 5/24; A47L 5/26; A47L 5/28; A47L 5/367; A47L 5/225; A47L 9/0673; A47L 13/00; A47L 13/10; A47L 13/20; A47L 13/24; A47L 13/16; A47L 13/17; B08B 3/00; B32B 5/00; B32B 5/024; B32B 5/026

See application file for complete search history.

(57) **CLAIM**

The ornamental design for a cleaning article, as shown and described.

DESCRIPTION

FIG. 1 is a front perspective view of a cleaning article, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1. The dash-dot-dash broken lines encircling the enlarged views are for annotative purposes only and form no part of the claim thereof.

1 Claim, 9 Drawing Sheets
